UNITED STATES PATENT OFFICE.

MERRILL E. CLARK, OF BRADFORD, PENNSYLVANIA.

BALL-BEARING.

1,158,106.

Specification of Letters Patent.

Patented Oct. 26, 1915.

Application filed March 16, 1909. Serial No. 483,741.

To all whom it may concern:

Be it known that I, MERRILL E. CLARK, a citizen of the United States, residing at Bradford, in the county of McKean and 5 State of Pennsylvania, have invented a certain new and useful Improvement in Ball-Bearings, of which the following is a specification, accompanied by drawings forming a part of the same, in which—

10 Figure 1 represents a side view of a ball bearing embodying my present invention, partly shown in sectional view on the plane of the broken line 1—1, Fig. 3, by the removal of one quarter of the bearing. Fig. 15 2 is a top view of the bearing with one quarter removed. Fig. 3 is a transverse sectional view on the plane of the broken line 3—3, Fig. 2. Fig. 4 is a transverse sectional view on the plane of the broken line 4—4, Fig. 1, 20 and Fig. 5 is a detached view of a portion of the ball race showing the arrangement of the balls contained therein.

Similar reference letters and figures refer to similar parts in the different views.

25 My present invention relates to a divided bearing or one in which the inclosing shell, or case is made in halves, and attached together by bolts or other suitable means, which enables the bearing to be divided and 30 applied to or removed from a shaft, and it consists in the construction and arrangement of parts as hereinafter described and pointed out in the annexed claims.

Referring to the accompanying drawings 35 1 denotes a rotating shaft inclosed in a ball bearing embodying my invention, comprising an outer shell 2 formed in halves and provided with lugs 3 to receive bolts 4 by which the two halves are united. The divided shell 2 is enlarged at its opposite ends 40 to provide space for two independent ball races, the race at one end being shown by the sectional views in Figs. 1, 2 and 3, but as that at the opposite end is a duplicate the 45 description of one will suffice. Inclosed within the shell 2 is a sleeve 5 having its ends enlarged to form a track 6 for the anti-friction balls 7. The enlarged end of the shell 2 is provided with a radial shoulder 8 against which rests an annular bearing plate or washer 9, preferably of steel, but divided in halves to correspond with the division between the halves of the shell 2. Opposing the ball track 6 formed upon the enlarged end of the sleeve 5 is a ring 10 also

formed in halves and receiving the outward pressure of the balls. The outer edge of the ring 10 projects slightly over the end of the sleeve 5 and abuts against the outer edge of a plate 11, also formed in halves to correspond with the division of the shell 2, and forming an inclosing wall for the outer end of the ball track, and having a clearance space 12 between the side of the plate 11 and the enlarged end of the sleeve 5. The ends of the shell 2 are extended beyond the plate 11 to receive a sheet metal dust cap 13, provided at its outer edge with a flange 14 which is attached to the ends of the shell 2 by screws 15. The space between the plates 9 and 11 is less than the combined diameters of the rows of balls inserted between them, which in the present instance are three in number, and in order to place the three rows between the plates 9 and 11 they are arranged in staggered relation to each other, with the center row of balls 16 overlapping the outer rows 17 and 18. The sleeve 5 divided to correspond with the division of the shell 2 is provided with lugs 19 to receive bolts 20 by which the halves of the sleeve are united, and within the sleeve 5 I place a bushing 21 of some anti friction metal, such as gun metal or bronze, which forms a contact with the shaft 1. Between the plate 11 and the dust cap 13 the space is filled with any suitable fibrous material 22, which is packed against the periphery of the shaft 1 in order to prevent the access of dust to the bearing and the escape of lubricating material.

In operation, the bushing 21 and sleeve 5 rotate with the shaft, turning the anti-friction balls 7 between the raceway 6 and the outer bearing ring 10, but if by accident the free movement of the sleeve 5 within the outer shell is impeded, as might occur by the breakage of a ball, for example, the shaft 1 is free to rotate within the bushing 21 while the sleeve 5 is held stationary.

I claim,

1. The combination, with a rotatable shaft, of a bushing surrounding said shaft, a two part sleeve, having a peripheral ball track at each end, surrounding and rotatable upon said bushing, an outer shell having interior ball tracks corresponding to the tracks of said sleeve, a series of antifriction balls carried within the races formed by said tracks and means for retaining said balls

within said races, said retaining means permitting endwise movement of the sleeve within said outer shell.

2. The combination, with a rotatable shaft, of a bushing surrounding said shaft, a two part sleeve, having an enlarged section at each end to form a peripheral ball track, rotatable upon said bushing, an outer shell provided with enlarged recessed end portions to coöperate with the ball tracks of said

sleeve to form ball races, a plurality of anti-friction balls carried within each of said ball races and means for retaining said balls within said races, said retaining means permitting endwise movement of the sleeve 15 within said outer shell.

MERRILL E. CLARK.
